PAGE 4.

Figure 1 is a front perspective view of a portable electric sander embodying my new design;

Figure 2 is a rear perspective view thereof;

Figure 3 is an elevational view thereof as seen from the right side of Figure 1;

Figure 4 is a top plan view thereof;

Figure 5 is a front elevational view thereof; and

Figure 6 is a rear elevational view thereof.

The dominant features of my design reside in those portions thereof shown in full lines.

I claim:

The ornamental design for a portable electric sander, as shown and described.
